United States Patent Office.

JAMES PATERSON, OF ELIZABETH, NEW JERSEY, ASSIGNOR TO EDWARD HARVEY, OF BROOKLYN, NEW YORK.

Design No. 2,692, dated July 2, 1867.

DESIGN FOR A FLOOR-CLOTH PATTERN.

The Schedule referred to in these Letters Patent and making part of the same.

TO ALL WHOM IT MAY CONCERN:

Be it known that I, JAMES PATERSON, of the city of Elizabeth, county of Union, State of New Jersey, have invented and produced a new and original Design to be Printed on Floor Oil-Cloth or other fabric, in colors similar to those in the drawings accompanying this specification, or in other colors substituted in place of those printed on the drawings herewith; and I do hereby declare that the drawings accompanying this specification do give and convey a more defined and thorough description of the nature of my invention, to any one skilled in the art of printing floor oil-cloth, than it is in the power of language otherwise to convey, and is sufficient to enable any one skilled in printing floor oil-cloth to use my invention.

What I claim as my invention, and what I desire to secure by Letters Patent, is—

The design hereunto annexed when made by being printed on floor oil-cloth or other fabric in the form similar to the drawings accompanying this specification.

JAS. PATERSON.
